[57] CLAIM

The ornamental design for a curved circular anastomosis surgical stapler, as shown in the accompanying drawings.

DESCRIPTION

FIG. 1 is a top plan view of a curved circular anastomosis surgical stapler, showing our new design;

FIG. 2 is a view of one side of the device;

FIG. 3 is an end view of the device, looking from the right of FIG. 2;

FIG. 4 is a view of the side of the device opposite that of FIG. 2;

FIG. 5 is an end view of the device, looking from the left of FIG. 2; and

FIG. 6 is a bottom plan view of the device, looking from the bottom of FIG. 4.

FIG. 1

FIG. 2

FIG. 3
